US00D552606S

(12) **United States Design Patent** (10) **Patent No.:** **US D552,606 S**
Swanson et al. (45) **Date of Patent:** **** Oct. 9, 2007**

(54) **HANDHELD WIRELESS COMMUNICATION DEVICE**

(75) Inventors: **Mark R. Swanson**, Wisconsin Rapids, WI (US); **Peter William Jungwirth**, Wisconsin Rapids, WI (US); **Jason Boon**, Sun Prairie, WI (US); **John W. Grosz**, Waupun, WI (US)

(73) Assignee: **Renaissance Learning, Inc.**, Wisconsin Rapids, WI (US)

(**) Term: **14 Years**

(21) Appl. No.: **29/252,642**

(22) Filed: **Jan. 25, 2006**

(51) **LOC (8) Cl.** **14-02**

(52) **U.S. Cl.** **D14/346**

(57) **CLAIM**

We claim the ornamental design for a handheld wireless communication device, as shown and described.

DESCRIPTION

FIG. 1 is a perspective view of the design for a handheld wireless communication device;

FIG. 2 is a front view of the design of FIG. 1;

FIG. 3 is a rear view of the design of FIG. 1;

FIG. 4 is a left side view of the design of FIG. 1 (the right side being a mirror image of the left side);

FIG. 5 is a top view of the design of FIG. 1; and,

FIG. 6 is a bottom view of the design of FIG. 1.
